(57) CLAIM

The ornamental design for a display screen or portion thereof with icon, as shown and described.

DESCRIPTION

FIG. 1 is a front image for a display screen or portion thereof with icon showing our new design; and,
FIG. 2 is an enlarged front view of the graphical user interface
of FIG. 1.

The broken lines are for environmental purposes only and form no part of the claimed design.

The broken-line outline of a square shown with a short-and-long dash pattern in FIGS. 1 and 2 illustrates the bounds of the icon and forms no part of the claimed design.

1 Claim, 2 Drawing Sheets
